CLAIM

The ornamental design for a toy gun, as shown and described.

DESCRIPTION

FIG. 1 is a perspective view of a toy gun, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view of the toy gun shown with environment;

FIG. 10 is a another perspective view shown with an alternative environment;

FIG. 11 is an enlarged view of portion 11 shown in FIG. 1; and,

FIG. 12 is an enlarged view of portion 12 shown in FIG. 2. The evenly broken lines shown in the drawings illustrate environment and portions of the toy gun that form no part of the claimed design.

The dot-dash broken lines in FIGS. 1-2 and 11-12 depict the boundaries of the enlargement indicia and form no part of the claimed design.

1 Claim, 12 Drawing Sheets
